HENRY E. STEVENS, JR., OF NEW YORK, N. Y.

CABINET FOR DISK RECORDS.

1,145,712.

Specification of Letters Patent.

Patented July 6, 1915.

Application filed March 9, 1914. Serial No. 823,394.

To all whom it may concern:

Be it known that I, HENRY E. STEVENS, Jr., a citizen of the United States, and a resident of the city of New York, borough of Manhattan, in the county and State of New York, have invented a new and Improved Cabinet for Disk Records, of which the following is a full, clear, and exact description.

This invention relates to furniture and has particular reference to cabinets designed especially for holding disk records in close compact relation to one another.

Among the objects of the invention is to provide means of a simple and reliable nature whereby the operator may select and remove any desired records from the cabinet with facility.

A further object of the invention is to manipulate the records as to reduce the danger of damage to the same to a minimum.

A still further object of the invention is to provide a filler for cabinets now on the market, said filler constituting the main features of this invention.

The foregoing and other objects of the invention will hereinafter be more fully set forth and claimed and illustrated in the drawings forming a part of this specification in which like characters of reference indicate corresponding parts in all the views, and in which—

Figure 1 is a vertical sectional view showing a preferred form of this invention, its relation to a cabinet and a disk record supported normally therein; Fig. 2 is a front elevation corresponding to Fig. 1; Fig. 3 is a horizontal section on the line 3—3 of Fig. 1; and Fig. 4 is a transverse sectional detail on the line 4—4 of Fig. 1.

The several parts of the device may be made of any suitable materials, and the relative sizes and proportions, as well as the general design of the mechanism, may be varied to a considerable extent without departing from the spirit of the invention hereinafter more fully set forth and specifically claimed.

Referring more particularly to the drawings I show at C a cabinet of any suitable design or type with which my improvement is adapted to be used, the illustration in this respect being diagrammatic.

The main parts of the filler consist of upper and lower members 10 and 11 respectively, each having guiding means shown herein as grooves 12 and 13 respectively,

arranged in vertically aligned pairs and adapted to receive individual records D therein where they are held in normal position in the cabinet. The members 10 and 11 are slightly inclined downwardly toward the rear of the cabinet and have their grooves substantially parallel to each other, the vertical space between the bottoms of each pair of grooves being substantially equal to or slightly greater than the diameter of the record. The ribs 14 constituting the side walls of the grooves or the guards, preventing one record from contacting with another, are preferably quite narrow or thin so as to permit as much room as possible to be occupied by the records in close relation to one another. The depth of the ribs 14, for simplicity of construction, may be comparatively slight, but as to this and other minor details of construction I do not wish to be limited. By virtue of the slight incline at which the guide members are set, the records when inserted into the guiding and holding grooves roll freely back toward the rear portion of the cabinet into normal position where they remain until they are to be selected and withdrawn from the cabinet.

Any suitable means may be provided to start the records from their normal position so that their front edges may be grasped readily by the operator's fingers and whereby they may be withdrawn from the cabinet. The form of ejector, which I prefer to use and show herewith, comprises a slidable or bodily movable member having a bar 15 guided along parallel to the member 11 and in the same vertical plane as the records supported by said member. At the rear end of the bar 15 is arranged, preferably integrally, an angularly disposed arm 16 which is adapted to lie normally near the rear portion of the record and having a slightly flattened and broadened end 16' adapted to bear against the periphery of the record when the ejector is moved bodily outwardly. At the front end of the bar is secured a finger piece 17 extending at an angle from the bar 15 whereby the ejector may be readily drawn outwardly for the purpose of starting the record from normal position. The finger pieces of alternate ejectors constituting a series are preferably of the same length, but one series of the finger pieces are preferably shorter than the other series and arranged slightly farther from the member 11, whereby, while the

records may be banked closely together, there is no difficulty in selecting and ejecting any of the disks because of the accessibility of the finger pieces to the operator's fingers, 5 otherwise the actuators or ejectors are or may be all substantially alike both in construction and operation.

The guiding and supporting member 11 is supported upon transverse sills 18 and 19. 10 The sill 18 is thicker than the other according to the desired amount of inclination for the member 11. The bars 15 of the ejectors are maintained in proper spaced parallel relation to one another and adapted for 15 slideable movement selectively between the member 11 and the sills 18 and 19 by any suitably arranged grooves or the like. For this purpose I have indicated the bottom surface of the member 11 as provided with 20 grooves 20, each groove 20 being arranged preferably beneath the longitudinal center of a groove 13 in which a record to be ejected is normally held.

When the operator selects a record and 25 wants to start it from its normal position in the cabinet, a pull on the finger piece 17, which may bear a number or be associated with a number on the face of the cabinet corresponding to the index number of the 30 selection desired, will slide the ejector forwardly, causing the arm 16 to start the record outwardly or up the inclined groove 13, and if the record is desired to be used immediately the operator will grasp it and 35 withdraw it from its place between the two next adjacent records which are left undisturbed by this operation. The angle of inclination of the member 11 being slight and much less than the angle of friction between the ejector and the guiding means 40 therefor, the ejector may remain in its projected position until the record is returned to its place, when the action of the record rolling back to normal position will carry 45 its ejector back with it to its normal position. While the front end of the ejector thus remains in its outer position, it may serve, at least in a degree, as an indicator to assist the operator in locating the place for the 50 record to be returned. The ejector thus constructed is of a very simple nature and the friction incident to its sliding movement is practically negligible.

Any suitable means may be provided to 55 prevent the rotation of the ejector whereby it is always maintained in such position that the arm thereof will be in the same plane as the record and directly in the rear of the rear portion of the record. In this connection attention is called to a comb-like abutment 21 extending horizontally along the rear portion of the structure, the same being shown secured to the front face of the rear wall 22 of the filler. Said rear wall constitutes the main connection between the

members 10 and 11, maintaining them in proper relation even though the filler be removed from the cabinet. The filler may also comprise, for this purpose, a bottom plate 23 connected at its rear end to the back wall 70 22 and serving to support the member 11 and the sills 18 and 19. The abutment 21 is provided with a slot 24 directly in the rear of each of the records and hence in the same vertical plane therewith. In this slot is 75 located the arm 16 of the ejector, the shoulder 25 at the rear end of the slot 24 constituting a convenient positive stop limiting the rearward movement of the ejector. The member 11 is preferably of a length such that the rear end 26 thereof is spaced from 80 the normal position of the arm 16 and serves as a convenient stop limiting the forward movement of the ejectors. In other words, the vertical planes coinciding with the rear end or shoulder 26 of the member 11 and the stop shoulders 25 of the abutment represent the extent of slideable movement of the ejectors forwardly and rearwardly. The metal or material of which 85 the ejectors are made may be of small caliber, less in width than the thickness of a record, and the slots 24 in which the arms 16 operate are, therefore, necessarily narrower than the thickness of the records. 90 The front edge 27 of the abutment, therefore, constitutes a convenient and effective positive stop, limiting the rearward movement of the records and serves to normally support the same in position, whereby the 95 strain incident to the weight of the records is relieved from the ejectors. Since the bars 15 of the ejectors are held and guided in the grooves between the member 11 and sills 18 and 19, it is obvious that the coöperation between the arms 16 and their guiding slots 24 will positively insure against 100 any rotation of the ejectors around the axes of the bars 15 with the result that the ends 16' of the arms will always be in the rear 110 of the records.

Without being unnecessarily limited to any particular form or general shape of the members 10 and 11 I prefer to make them of straight material, and, therefore, the bottoms of the grooves 12 and 13 are substantially plane throughout the principal portions thereof. In each of the grooves 13, however, I provide means to check and temporarily hold the record therein after it 120 has been started outwardly from its normal position in the cabinet. As a convenient means for accomplishing this purpose, I provide a slight depression or pocket 28 into which the record rolls. This pocket or depression is just deep enough preferably to prevent the record from rolling by gravity rearwardly therefrom when the ejector 125 brings the record into position to roll into the pocket. It is not deep enough, however, 130

to allow the record to be withdrawn from the groove 12 in the upper member 10. The bars or ribs 14, therefore, are always effective to keep each record safely spaced from the other records. Among the principal purposes of the pockets 28 is to provide a means for temporarily holding any selected records out of normal position until they may be applied to the machine. It is a quite usual practice for an operator to have a number of selections under contemplation at one time or while any selection is being rendered, and the means provided herewith for selecting, ejecting and temporarily holding the records is found most convenient for this purpose. The pockets do not interfere in any manner with the prompt return of the records to their normal position in the cabinet as they roll rearwardly from the outer ends of the grooves 13.

Having thus described my invention, I claim as new and desire to secure by Letters Patent:—

1. In a disk record cabinet, the combination with guiding and supporting means for a record disk holding the same normally in a vertical plane, of an ejector comprising a bar movable longitudinally along the guiding means and having an integral angularly arranged arm extending in the rear of the disk, and means to limit the slidable movement of the ejector, substantially as set forth.

2. In a disk record cabinet, the combination with upper and lower spaced guide members having pairs of parallel grooves to receive and hold a series of individual records in vertical planes, of a series of ejectors for starting any selected records from normal position, each ejector lying and movable in the plane of the record to which it pertains and including a straight longitudinally movable bar and a rigid angularly disposed arm integral with the bar, said arm lying in the rear of the record, and a rigid member lying in the rear of all of the records and serving to limit the rearward movement thereof and prevent rotation of the ejector.

3. In a device of the character set forth, the combination of a supporting guide member having spaced parallel grooves to receive and support a closely associated series of records, means to support and properly space from one another the portions of the records opposite said member, and a series of independently selected and operated ejectors associated with said supporting and guiding member, each ejector comprising a bar guided for sliding movement along and parallel to said member, and an arm integral with said bar and extending at an angle therefrom in the same plane as the record to be ejected thereby, said ejector bar also having secured to the end thereof opposite the arm a finger piece whereby the ejector may

be drawn outwardly to start a record from normal position.

4. In a cabinet for disk records, the combination of a guiding and supporting member having spaced means for a series of records arranged in close parallel planes, a series of ejectors pertaining to the several records, each ejector comprising a bar slidable parallel to the guiding and supporting means and an integral rigid arm arranged at an angle to the bar in the rear of the record to be ejected thereby, and means co-operating with the arm to prevent rotation of the ejector around the axis of the bar.

5. In a cabinet for disk records, the combination of a main guiding and supporting member for individual independently movable records, a series of ejectors each comprising a slidable bar and an integral rigid arm arranged at an angle to one end of the bar, and means co-operating with the several ejector arms constituting means to prevent rotation thereof around the axes of the several bars and also constituting positive stop means to limit the movement of the ejectors in one direction.

6. In a disk record cabinet, the combination of main guiding and supporting means for a closely arranged series of parallel records, a series of ejectors relating to the several records and movable independently of one another, each ejector being slidable and bodily movable in the plane of its record for starting such record from its normal position, each ejector including an integral rigid arm extending in the rear of the record and adapted to engage the periphery thereof, and a member serving to prevent rotation of the ejector and to limit its slidable movement.

7. In a cabinet for disk records, the combination of main guiding and supporting means for a plurality of parallel closely related records, a series of independently operable ejectors relating to the several records, each ejector comprising a straight bar and an arm extending from one end of the bar at an angle in the rear of the record to be started thereby, and an abutment arranged parallel to the records, said abutment co-operating with the several ejector arms to prevent rotation of the ejectors and limit the slidable movement thereof in one direction, said abutment also constituting positive stop means to limit the movement of the records in one direction and relieve the strain thereof from the ejectors under normal conditions.

8. In a cabinet for disk records, the combination of a pair of oppositely arranged parallel guide members for a series of closely related records, one of the guide members having a series of guide grooves in the face thereof opposite the records and in the same planes as the records, a series of ejectors

having straight bars movable in said grooves and also having arms extending at an angle from the rear ends of the bars in the rear of the several records, and means coöperating with said arms to prevent rotation of the bars in said grooves and maintaining the arms in the rear of the records.

9. In a device of the character set forth, the combination of main supporting and 10 guiding means for closely related parallel records, and a series of independently operable ejectors relating to the several records, each ejector comprising a slideable bar, a 15 finger piece at the outer end and an arm at the rear end, the ejector arms extending in

the rear of the several records and the finger pieces being arranged in a plurality of groups, the finger pieces of one group being shorter and farther outward from the cabinet than those of the other group, and the 20 individuals of the several groups being arranged in alternation.

In testimony whereof I have signed my name to this specification in the presence of two subscribing witnesses.
